UNITED STATES PATENT OFFICE.

MAURICE PIVERT, OF NEW ORLEANS, LOUISIANA.

MIXING-VALVE FOR EXPLOSION-ENGINES.

SPECIFICATION forming part of Letters Patent No. 724,328, dated March 31, 1903.

Application filed June 5, 1902, Serial No. 110,813. (No model.)

To all whom it may concern:

Be it known that I, MAURICE PIVERT, a citizen of the United States, and a resident of New Orleans, in the parish of Orleans and 5 State of Louisiana, have invented a new and Improved Mixing-Valve for Explosion-Engines, of which the following is a full, clear, and exact description:

The invention relates to explosion-engines 10 of the four-cycle type; and its object is to provide a new and improved mixing-valve for explosion-engines whereby a perfect mixture of the air and the gasoline or other explosive vapor used is obtained to insure a powerful 15 and regular explosion of the mixture in the working chamber of the engine.

The invention consists of novel features 20 and parts and combinations of the same, as will be more fully described hereinafter and 25 then pointed out in the claims.

A practical embodiment of the invention is represented in the accompanying drawings, forming a part of this specification, in which similar characters of reference indicate corresponding parts in all the views.

Figure 1 is a sectional side elevation of the improvements as applied. Fig. 2 is a plan view of the regulating feed-valve. Fig. 3 is a sectional plan view of the improvement on the 30 line 3 3 of Fig. 1, and Fig. 4 is a similar view of the same on the line 4 4 of Fig. 1.

The explosion-engine on which the improved valve is employed may be of any approved construction—such, for instance, as 35 shown and described in the application for Letters Patent of the United States filed by me under even date herewith; and the engine is provided with a casing A, having a working chamber B, extending sidewise and 40 into which opens the admission-valve C, normally seated on the valve-seat D', formed on the lower end of a valve-plug D, screwed or otherwise secured to the top of the chamber B, as plainly indicated in Fig. 1. Opposite 45 the valve C is arranged an inwardly-opening exhaust-valve E, normally held on a valve-seat B', formed in the bottom of the chamber B and leading to the exhaust-chamber B². The exhaust-valve E is periodically opened 50 by a suitable mechanism actuated from the main shaft of the engine to allow the prod-

ucts of combustion to pass from the chamber B into the exhaust-chamber B².

In the top of the valve-plug D screws the valve-casing F, having its interior in communication with the valve-seat D' by the apertured bottom D² of the valve D, the apertures in the said bottom being covered by a wire screen or netting G to prevent dust and other impurities from passing into the engine. The top portion of the interior of the valve-casing F is formed with a conical valve-seat F', on which is normally seated a conical valve H, secured on the upper end of a valve-stem I, carrying at its lower end the valve C, mounted to slide in a suitable central bearing D³, extending upwardly from the bottom D² of the plug D.

A spring J rests at its lower end on the screen G and presses with its upper end 70 against the under side of the conical internal valve H to hold the valves H and C normally to their seats F' and D'. A gasoline-feed channel F² leads into the apex end of the valve-seat F', and the said channel F² connects with the apex end of a conical valve-seat F³, into one side of which opens the feed-groove F⁴, connected with a gasoline-supply pipe K, screwed or otherwise secured 75 to the valve-casing F.

A conical regulating feed-valve L extends into the seat F³ and has its threaded stem L' screwing in the top of the valve-casing F, and on the outer end of the said stem L' is secured a toothed wheel L², adapted to be taken 85 hold of by the operator to turn the stem L', so as to screw the same inward or outward to bring the valve L nearer to or farther from the valve-seat F³ to regulate the amount of gasoline passing from the feed-groove F⁴ to the 90 channel F². A spring N engages the wheel L², so as to hold the valve L against accidental movement. Air-openings F⁵ are formed in the valve-casing F and lead to the base end of the valve-seat F', as plainly indicated in 95 Fig. 1.

The operation is as follows: When the piston in the cylinder of the engine is on the suction-stroke, then the valve C opens inwardly against the tension of the spring J, thus opening the valve H to allow gasoline to pass from the supply-pipe K by the groove F⁴, seat F³,

and channel F^2 on to the apex end of the said conical valve H , whereby the gasoline is spread and flows downward on the valve and seat, and as at the same time the air is 5 sucked in through the openings F^5 it is evident that this incoming air comes immediately in contact with the gasoline, and consequently a thorough mixture of the air and gasoline takes place, and this mixture passes 10 down through the valve-casing F , through the screen G and apertures in the bottom D^2 , to finally pass through the open valve-seat D' into the chamber B and cylinder of the engine. On the return or compression stroke 15 of the piston the explosive mixture in the cylinder is compressed and finally ignited to send the piston down on the power-stroke, and when the piston returns the valve E is opened to cause exhaust of the products of 20 combustion from the chamber B to the exhaust-chamber B^2 . On the next downward stroke of the piston the suction period sets in and the above-described operation is then repeated. When the piston reaches the end 25 of the suction-stroke, the valves C and H move immediately to their seats by the action of the spring J , and the said valves remain closed until the next suction period sets in.

Having thus described my invention, I 30 claim as new and desire to secure by Letters Patent—

1. A mixing-valve for explosion-engines, comprising a valve-casing formed with an internal conical valve-seat, a feed-channel leading 35 to the apex end of the seat, the said casing having air-inlet openings leading to the base end of the valve-seat, a conical valve for engaging the valve-seat, a stem carrying said valve, a second valve carried by the stem 40 and adapted to engage a valve-seat carried by the casing, and a partition having apertures therein leading from the interior of the casing to said valve-seat, as set forth.

2. A mixing-valve for explosion-engines, 45 having a valve-casing formed with an internal valve-seat, a gasoline-feed channel leading to the seat at the apex end, air-openings in the walls of the said valve-casing, leading to the base end of the said seat, a plug carrying the 50 valve-casing and having an external valve-seat, and two valves moving in unison and adapted to be seated on the said seats, as set forth.

3. A mixing-valve for explosion-engines, 55 having a valve-casing formed with an internal valve-seat, a gasoline-feed channel leading to the seat at the apex end, air-openings in the walls of the said valve-casing leading to the base end of the said seat, a plug carrying the 60 valve-casing and having an external valve-seat, two valves moving in unison and adapted to be seated on the said seats, and a spring for normally holding the valves to their seats, as set forth.

4. A mixing-valve for explosion-engines, 65 having a valve-casing formed with an internal valve-seat, a gasoline-feed channel leading to

the seat at the apex end, air-openings in the walls of the said valve-casing, leading to the base end of the said seat, a plug carrying the 70 valve-casing and having an external valve-seat, two valves moving in unison and adapted to be seated on the said seats, and a screen over the apertured bottom of the plug, as set forth. 75

5. A mixing-valve for explosion-engines, having a valve-casing formed with an internal conical valve-seat, to the apex end of which leads a feed-channel for feeding the gasoline to the valve-seat, air-openings leading to the 80 base end of the seat and formed in the sides of the said valve-casing, a conical valve on the said internal conical valve-seat, a stem carrying the valve, a plug into which screws the said valve-casing, having an external 85 valve-seat leading to the working chamber of the engine, the said plug also having an apertured bottom for establishing communication between the interior of the valve-casing and the valve-seat of the said plug, and a 90 spring for holding the said valves normally to their seats, as set forth.

6. A mixing-valve for explosion-engines, having a valve-casing formed with an internal conical valve-seat, to the apex end of which 95 leads a feed-channel for feeding the gasoline to the valve-seat, air-openings leading to the base end of the seat and formed in the sides of the said valve-casing, a conical valve on the said internal conical valve-seat, a stem 100 carrying the valve, a plug into which screws the said valve-casing, having an external valve-seat leading to the working chamber of the engine, the said plug also having an apertured bottom for establishing communication 105 between the interior of the valve-casing and the valve-seat of the said plug, a spring for holding the said valves normally to their seats, and a regulating feed-valve for controlling the amount of gasoline passing to the 110 said feed-channel, as set forth.

7. A mixing-valve for explosion-engines, comprising a valve-casing communicating with the working chamber of the engine, a valve controlling said communication, the 115 said casing being formed with an internal conical valve-seat, a fuel-feed channel leading to the apex end of the seat, a conical valve adapted to be seated on the said seat, and moving in unison with the first-mentioned 120 valve, the said casing having air-inlets opening into the casing opposite the conical valve, and means for controlling the amount of fuel passing to the feed-channel, as set forth.

8. A mixing-valve for explosive-engines, 125 comprising a valve-casing formed with an internal conical valve-seat, a feed-channel leading to the apex end of the seat, a conical valve the apex portion of which is adapted to engage the valve-seat, the base portion of the 130 conical valve extending beyond the valve-seat and spaced from the inner surface of the valve-casing, the said casing having air-inlet openings leading to the said space, a stem

carrying said valve at one end, a second valve carried by the stem at the other end and adapted to engage a valve-seat carried by the casing, and a partition having apertures leading from the interior of the casing to said valve-seat, as set forth.

5 In testimony whereof I have signed my

name to this specification in the presence of two subscribing witnesses.
